TAPE MAGAZINE OF A MAGNETIC SOUND
RECORDING APPARATUS

Colin D. Murdoch, San Leandro, Calif., assignor to John
F. Cady, San Francisco, Calif.

Application November 26, 1956, Serial No. 43,940

Term of patent 14 years

(Cl. D26—14)

Fig. 1 is a perspective view of a tape magazine for magnetic sound recording apparatus, showing my new design;

Fig. 2 is a top plan view thereof; and

Fig. 3 is a front elevational view thereof.

I claim:

The ornamental design for a tape magazine for magnetic sound recording apparatus, substantially as shown.
